UNITED STATES PATENT OFFICE.

WILLARD L. POLLARD, OF EVANSTON, ILLINOIS.

DESIGN FOR AN AUTOMOBILE TOP.

59,430.

Specification for Design.

Patented Oct. 18, 1921.

Application filed August 6, 1921. Serial No. 490,415. Term of patent 14 years.

To all whom it may concern:

Be it known that I, WILLARD L. POLLARD, a citizen of the United States, residing at Evanston, in the county of Cook and State of Illinois, have invented a certain new, original, and ornamental Design for an Automobile Top, of which the following is a specification, reference being had to the accompanying drawing, forming a part thereof.

Figure 1 is a side elevation of an automobile showing my design for side and top construction; and

Fig. 2 is a detail perspective view showing the junction between the door body and the glass panel, showing the glass seated in a channel, the channel being in turn seated in a channel in a supporting frame, this view being made, not to show the interior construction, but to bring out the general contour.

I claim:

The ornamental design for an automobile top, substantially as shown.

WILLARD L. POLLARD.
